Primary Examiner — Sanjeev Paul

(74) Attorney, Agent, or Firm — True Shepherd, LLC;
Andrew Cheng(57) CLAIM

The ornamental design for a pillow, as shown and described.

DESCRIPTION

FIG. 1 is a front, right and top perspective view of a pillow, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dotted lines shown in the drawings represent sewing lines and form a part of the claim.
